CLAIM

I claim the ornamental design for a garden pathway lighting
fixture, as shown and described.

DESCRIPTION

FIG. 1 is a front elevational view of a garden pathway
lighting fixture showing my new design;

FIG. 2 is a rear elevational view thereof;

FIG. 3 is a right side elevational view thereof;

FIG. 4 is a left side elevational view thereof;

FIG. 5 is a top plan view thereof; and,

FIG. 6 is a perspective view.

The surface(s) or portion(s) of the article not shown in the
drawing or described in the specification form(s) no part of
the claimed design.
